UNITED STATES PATENT OFFICE.

WILLIAM R. HILDEBRAND, OF CHICAGO, ILLINOIS.

RUBBER-HEEL PROTECTOR.

1,326,503.

Specification of Letters Patent. Patented Dec. 30, 1919.

Application filed March 31, 1916. Serial No. 87,915.

To all whom it may concern:

Be it known that I, WILLIAM R. HILDEBRAND, a citizen of the United States, residing at Chicago, in the county of Cook 5 and State of Illinois, have invented certain new and useful Improvements in Rubber-Heel Protectors, of which the following is a specification.

My invention relates to resilient or rubber 10 heels and has particular reference to means for protecting same against wearing out too speedily. The object of the invention is to provide metallic wearing surface for rubber heels without unduly interfering with 15 their elasticity, or with even wearing thereof, or with the uniformity of their elasticity throughout the body of the heel at each impact.

With these objects in view the invention 20 consists in the novel construction of heel hereinafter described in detail, illustrated in the accompanying drawing and more particularly pointed out in the appended claim.

25 In the drawing—

Figure 1 is a bottom elevation of a heel or other bottom portion of a shoe, embodying my invention.

Fig. 2 is a section on line X—X of Fig. 1. 30 Fig. 3 is an enlarged and broken away section of the heel.

In the several views 2 represents the body of a rubber heel; 3 represents one form of metal studs; 4, another form; 5, still another 35 form, and 6 a fourth modification.

Each stud comprises a rod 8 bent in U-form having spread apart ends which ends diverge toward the open end of the U, and prevent accidental displacement or loss of 40 the studs. The stud is molded in; that is, the rubber in plastic or semi-liquid form is poured or cast around the lugs in suitable molds provided for this purpose. 9, 9 are

counterbores for the heads of the usual screws engaging holes 10, by means of which the 45 heel is secured to the boot or shoe.

The many attempts heretofore made to prevent uneven wearing down of one corner of a rubber heel has resulted in plates fastened by screws which interfered with the 50 elasticity of the area covered by the plate, and, moreover, the screw or spur fastenings have generally failed to hold the plate. In the present invention the metallic contact points respectively cover small areas between 55 which there is retained the desired resiliency or elasticity, and by confining the tubules, studs, or spurs within a horizontal area close to the wear surface, leaving a backing of solid rubber, the anti-wear elements cause very little, if any, interference with the functions of a solid and unshod rubber heel disk.

By providing this form of metallic contact points, the latter may be tempered to 65 any desired extent, because the question of bending strains tending to break the metal, is not involved in this form of construction. Except for the brevity of life of a rubber heel its use would be universal, since it is 70 universally conceded that it is preferable, more agreeable, and less unduly and unnaturally jarring than the leather substitute for nature's elastic heel.

Having thus described my invention, I 75 claim as new and desire to secure by Letters Patent—

The combination with a rubber heel, of a bar or wire bent U-shape with spread apart ends embedded in the heel, the embedded 80 portion thereof diverging toward the open end of the U.

In testimony whereof I have hereunto signed my name.

WILLIAM R. HILDEBRAND.
